PICKER STICK CHECK FOR LOOMS

Harry A. Davis, Hopedale, Mass., assignor to
Crompton & Knowles Loom Works, Worcester,
Mass., a corporation of Massachusetts

Application August 22, 1940, Serial No. 353,711

10 Claims. (Cl. 139—163)

This invention relates to improvements in picker stick checks for looms and it is the general object of the invention to utilize motion of the picker stick induced by the shuttle to check or resist motion of the stick and thereby retard the shuttle.

In the usual loom the greater part of shuttle momentum is absorbed by frictional contact with the binder but there is usually a residual amount of momentum which remains to be absorbed during the last part of the shuttle boxing. In many looms this residual momentum is absorbed by the picker with harmful results to itself. The picker is usually connected in some way to the picker stick so that motion of the picker in an outward direction toward the end of the lay will be transmitted to the picker stick. It is an important object of my present invention to provide means whereby the time during which the picker is in contact with and absorbing the residual energy of the moving shuttle can be distributed over a sufficient period to reduce wear and strain on the picker.

It has been customary in the past to employ a type of picker stick check including a strap the motion of which is resisted by a spring or some form of yielding friction clamp. It is another object of my present invention to provide a flexible strap which will be moved by the picker stick during the latter part of shuttle boxing and in its motion act to cause other means to increase the frictional resistance between the picker stick and the strap.

It is a more specific object of my present invention to provide a strap having one end thereof anchored to the lay and extending around the outer edge of the picker stick and then inwardly toward a rotatable element to which it is attached. When the stick is moved outwardly the strap will act to turn the rotatable element and the latter will rotate a cam or the like to move one end of a lever into a position to resist motion of the picker stick. The lever may if desired act on the strap to force it against the stick.

It is a still further object of my present invention to provide resilient means for returning the strap and lever to normal position in such a way as to locate the picker stick a short distance inside its extreme outer position. In this way assurance is given that the stick will be in an initial checking position and able to receive motion from the latter part of the shuttle flight and communicate this motion through the strap to the checking lever.

Another object of my invention is to make the

lever in two parts which are yieldingly held together, one of the parts to derive its motion from a cam and the other part to move to a position where it can resist picker stick motion. The yielding connection will permit the second part of the lever to be arrested in its motion should the cam act to give the lever too large an angular motion.

With these and other objects in view which will appear as the description proceeds, my invention resides in the combination and arrangement of parts hereinafter described and set forth.

In the accompanying drawing, wherein a convenient embodiment of my invention is set forth, Fig. 1 is a rear elevation of one end of a loom having my invention applied thereto,

Fig. 2 is an enlarged horizontal section on line 2—2 of Fig. 1,

Fig. 3 is an enlarged rear elevation of part of the mechanism shown in Fig. 1 and looking in the direction of arrow 3, Fig. 2,

Fig. 4 is a vertical section on line 4—4 of Fig. 2,

Figs. 5, 6 and 7 are detail horizontal sections on lines 5—5, 6—6 and 7—7, respectively, of Fig. 4,

Fig. 8 is a horizontal section on line 8—8 of Fig. 3, and

Figs. 9 and 10 are vertical sections on lines 9—9 and 10—10, respectively, of Fig. 2.

Referring to the drawing, I have shown part of the loom frame 10 and a lay 11 having a shuttle box B at one end thereof to receive a shuttle S. The lay supports a picker spindle 12 along which slides a picker 13 propelled by a picker stick 14 pivotally mounted at 15 on a rocker iron or foot 16 extending from the lay axis or rocker shaft 17. The lay is supported by swords one of which is indicated at 18 supported on the shaft 17. A lug strap 19 extends around the outer edge of the picker stick and is connected by a sweep stick 20 to a picking arm 21 mounted on a picking shaft 22 on which is also mounted a picking cam 23. The bottom shaft 24 of the loom carries a picker ball arm 25 on which is mounted a picking ball 26 to cooperate with the cam 23 and rock the shaft 22 in a clockwise direction as viewed in Fig. 1 to move the picker stick inwardly or toward the right from the position shown in Fig. 1 to pick the shuttle. The picking motion will occur on alternate beats of the loom when the lay is at so-called top center and at its approximate midpoint when moving rearwardly.

When the shuttle arrives from the opposite

side of the loom it will enter the box B and will be retarded by the usual binder not shown but well understood. During the boxing of the shuttle a frictional force is applied to the shuttle, but this force ordinarily is not sufficient to bring the shuttle to rest before it strikes the picker. The residual momentum remaining in the shuttle as the latter approaches the end of its boxing movement is exerted against the picker and from the latter to the picker stick, tending to move the latter outwardly or in a left hand direction as viewed in Fig. 1 toward the adjacent end of the lay. After picking the stick will move outwardly or to the left as viewed in Fig. 1 but will be prevented from completing its outward motion by a mechanism to be described. Under normal running conditions therefore it will be understood that as the shuttle enters the box the picker stick is in its initial checking position a short distance from its extreme outward or final checking position, from one to two inches depending upon the setting of the parts to be described hereinafter, and as the shuttle nears the end of its stroke the stick will be given an outward movement.

The parts already described of themselves form no part of my present invention and may be made and operated as usual with the exception of the means for holding the picker stick in its initial checking position.

In carrying my present invention into effect I provide mechanism which comprises two co-operating parts one of which is given a direct motion by the picker stick as the shuttle nears the end of its stroke and the second of which is moved by the first into position to resist outward motion of the stick. I will first describe that part of the mechanism which is moved by the picker stick and then describe the second part which is actuated by the first part to check the stick.

The lay has secured thereto a depending bracket 27 the lower end of which is formed with a foot 28 to which a horizontal arm 29 is bolted. Extending upwardly from the arm 29 is a pivot pin 30 which is held in fixed position in the arm by a nut 31. Rotatable on this stud 30 is a cylindrical shell 32 the lower part of which has a tubular bearing 33 turnable on the stud. The latter is provided with a shoulder 34 to engage the arm 29 and a collet 35 located slightly above the bearing 33 to permit the latter to rotate freely on the stud. The shell 32 has an outer cylinder surface 36 which in this instance is preferably, though not necessarily, concentric with the axis of the stud 30. A flexible strap 37 has its rear end secured as at 38 to the cylindrical surface 36 and after being wrapped around a portion of the latter extends outwardly or to the left as viewed in Figs. 1 and 2 behind the picker stick and around the outer edge thereof. The front end of the strap then extends inwardly toward the center of the lay to be attached to the latter by a holder 39. In this way the forward end of the strap 37 is held fixed with respect to the lay while the rear end of the strap is fastened to and can cause rotation of the shell 32.

The bearing 33 has secured thereto a cam disk 45 held in adjusted position with respect to the bearing by a set screw 46. The cam may conveniently be in the form of an eccentric, as suggested in Fig. 8, but I do not wish to be limited to this form of cam. It is desirable however that the cam 45 have a low surface 47 and a high surface 48.

In order to limit angular motion of the parts

5 rotatable about the stud 30 I provide a stop collar 50 having a stop finger 51 to engage the arm 29 as at 52, see Fig. 7. The stop collar is held in angularly adjusted position on the bearing 33 by a set screw 53 and the finger 51 is held against its stop by means of a torsion spring 55 surrounding the upper extension of stud 30 above the collet 35. The lower end of the spring is held by the stud as at 56 while the upper end extends 10 into the shell 32, as at 57. A disk 58 is held to the stud by a screw 59 and prevents displacement of the spring but does not interfere with rotation of shell 32. The spring is attached to a head 56 which rotates with the shell 32. The spring permits turning of the shell 32 in a clockwise direction as viewed in Figs. 6, 7 and 8, and acts to return the shell and stop to normal position, and also draws the rear end of the strap inwardly, or 15 toward the center of the loom.

20 The second part of the structure is controlled by cam 45 and includes a second vertical stud 60 on arm 29 on which is rotatably mounted a pair of members one of which is a lever 61 and the other a picker stick checking arm 62. The lever has an arm 63 positioned for engagement with the cam disk 45 and has a second arm 64 extending toward the end of the lay. A rod 65 is slidably mounted in a nut 66 threaded into arm 64 and held in position by nut 67. An adjusting collar 68 secured to the rear end of rod 65 by screw 69 limits forward motion of the rod relatively to nut 66.

35 The forward end of rod 65 extends into a shoe 70 formed on the checking arm 62 and is enlarged as at 71 to limit rearward movement of the rod with respect to the shoe, see Figs. 2 and 10. A compression spring 75 surrounds rod 65 and lies between the nut 66 and the shoe 70 and tends normally to hold the latter in forward spaced position with respect to the arm 64. The 40 shoe 70 has an arcuate smooth vertical web 76 which lies behind and in contact with that part of the strap 37 which extends between the shell 32 and the picker stick. Except as restrained by relationships to be mentioned hereinafter the lever 61 and arm 62 are free to rotate on the stud 60.

45 Under normal conditions when the shuttle is travelling toward the box B, the parts will be in the full line position shown in Fig. 2 with the picker stick held in its initial checking position by spring 55 and ready to start outwardly with the shuttle during the last part of the shuttle travel in the box. Under these conditions the shoe 70 will be in light contact with the rear part of strap 37 and the arm 63 of lever 61 will engage the low surface 47 of cam 45. As the shuttle strikes the picker the picker stick will start to move to the left from the full line position of Fig. 2, and in doing so will move the rear part of strap 37 to the left, or toward the adjacent end of the lay, due to the fact that the front end of the strap is fixed to the lay. Movement of the strap will cause rotation of the shell 32 and cam 45 in a direction to move the wide part 48 of the cam rearwardly, thereby moving the arm 63 and causing a clockwise turning of lever 61 as viewed in Fig. 2. The corresponding forward motion of arm 64 moves the shoe 70 forwardly by a force transmitted through spring 75.

50 The strap 37 is pushed forwardly against the rear side of the stick when the shoe 70 advances to increase the frictional resistance offered by the strap to motion of the stick. By the time the picker stick has reached its outermost posi-

tion as indicated in dotted lines in Fig. 2, the cam will have moved sufficiently to place the wide or high area 48 against the end 63 of the lever and the shoe will have moved to its extreme forward position shown in dotted lines in Fig. 2, thereby increasing the wrap of the strap around the web 76.

The movement of lever 61 is due to a force derived originally from the shuttle and transmitted to the picker stick to cause the latter to move the rear part of the strap in an outward or left hand direction as viewed in Fig. 2. For this reason the checking force exerted on the stick is conditional upon the time of arrival of the shuttle in the shuttle box, and the rapidity with which the cam is turned to rock the lever, and therefore the rate at which the restraining force is applied by shoe 70, is proportional to the rate of travel of the shuttle. While spring 75 permits slight relative motion between the arm and the lever, in actual operation arm 62 and the lever 61 move together and therefore can be considered for all practical purposes as a unit rotatable about the stud 60. The spring 75 will yield if the cam rocks lever 61 through a distance more than that which can be accommodated by the flexing of the strap 37. The web 76 has been illustrated as having direct contact with the rear part of the strap 37, a construction which avoids direct engagement between the shoe and the picker stick, but I do not wish to be limited to this construction since the significant feature of the arm 62 is that it exerts a resisting force on the picker stick which is additional to the resistance offered by the strap 37 acting alone.

From the foregoing it will be seen that I have provided a picker stick check wherein outward motion of the stick acts to increase the frictional resistance offered to motion of the stick by a resisting element, such as the strap. It will further be seen that the picker stick causes motion of a part of the strap and that this motion is utilized to force the strap against the picker stick. More specifically, it will be seen that movement of the strap induced by the picker stick causes rotation of a cam element which acts on a lever to force the strap against the stick. Although I have shown the strap as having one end fixed with respect to the lay I do not wish necessarily to be limited to this construction, as it is sufficient if one part of the strap can be caused to move by the stick to actuate the lever rocking means.

Having thus described my invention it will be seen that changes and modifications may be made there in by those skilled in the art without departing from the spirit and scope of the invention and I do not wish to be limited to the details herein disclosed, but what I claim is:

1. In a picker stick check for a loom having a lay and a shuttle box thereon to receive a shuttle and having a picker stick to be given a movement toward the adjacent end of the lay by the shuttle as the latter approaches the end of its travel in the shuttle box, a flexible strap having one end thereof secured to the lay on one side of the picker stick and having the other end extending around the stick to be moved by the stick when the latter has said movement, a rotatable element mounted on the lay to which the strap is connected, a cam on the rotatable element, and a lever pivoted to the lay and having one end to be moved by the cam and having the other end positioned in engagement with the strap, movement of the strap by said movement of the picker

stick turning the rotatable member and causing the cam to rock said lever and cause said other end of the lever to move the strap into position to resist movement of the picker stick.

5 2. In a picker stick check for a loom having a lay and a shuttle box thereon to receive a shuttle and having a picker stick to be given a movement toward the adjacent end of the lay by the shuttle as the latter approaches the end of its travel in the shuttle box, a flexible strap supported by the lay and extending around the picker stick and having one end thereof moved by the stick when the latter has said movement, a cam connected to said one end of the strap to be moved by the latter, and a lever having one end thereof to engage the cam and the other end to move the strap toward the picker stick, movement of said one end of the strap causing movement of the cam and the latter rocking the lever in a direction to move said other end of the lever against the strap to move the latter frictionally against the stick to retard movement thereof.

10 3. In a picker stick check for a loom having a lay and a shuttle box thereon to receive a shuttle and having a picker stick to be given a movement toward the adjacent end of the lay by the shuttle as the latter approaches the end of its travel in the shuttle box, a flexible strap engaging the picker stick and having one end thereof movable by the stick when the latter has said movement, a lever pivoted on the lay, and means operated by the strap to move one end of the lever and thereby rock the lever when said end of the strap is moved by the picker stick, the other end of the lever engaging the strap and forcing the latter against the picker stick to retard motion of the stick toward the end of the lay when said lever is rocked by said means.

15 4. In a picker stick check for a loom having a lay and a shuttle box thereon to receive a shuttle and having a picker stick to be given a movement toward the adjacent end of the lay by the shuttle as the latter approaches the end of its travel in the shuttle box, a strap extending around the outer edge of the picker stick and having one end to be moved by the picker stick when the latter has said movement, a picker stick checking lever, and means operated by said strap to cause said lever to rock when said end of the strap is moved by the picker stick, said lever having a part thereof movable to a position to force the strap against the picker stick to assist in resisting motion of the picker stick toward the adjacent end of the lay when said lever rocks.

20 5. In a picker stick check for a loom having a lay and a shuttle box thereon to receive a shuttle and having a picker stick to be given a movement toward the adjacent end of the lay by the shuttle as the latter approaches the end of its travel in the shuttle box, means movable by the picker stick and acting to resist said movement of the picker stick toward the adjacent end of the lay, and other means moved by the first means against the latter to force said first means against the picker stick to increase the resistance offered by said first means to movement of the picker stick toward the adjacent end of the lay when said first means is moved by the picker stick.

25 6. In a picker stick check for a loom having a lay and a shuttle box thereon to receive a shuttle and having a picker stick to be given a movement toward the end of the lay by the shuttle as the latter approaches the end of its travel in the shuttle box, a strap extending around one

edge of the picker stick and having an end thereof movable by the picker stick when the latter has said movement, a picker stick checking lever normally in non-checking position, and means actuated by the strap when the latter is moved by the picker stick to move the lever against the strap and force the latter against the picker stick.

7. In a picker stick check for a loom having a lay and a shuttle box thereon to receive a shuttle and having a picker stick to be given a movement toward the end of the lay by the shuttle as the latter approaches the end of its travel in the shuttle box, the combination of two picker stick checking means one of which is normally in non-checking position and the other of which is normally in checking position and is moved by the picker stick when the latter has said movement, and mechanism actuated by said other means when the latter is moved by said picker stick to move the first named means against the other means to force the latter against the picker stick.

8. In a picker stick check for a loom having a lay and a shuttle box thereon to receive a shuttle and having a picker stick to be given a movement toward the end of the lay by the shuttle as the latter approaches the end of its travel in the shuttle box, a flexible strap to be engaged by the picker stick and have one end thereof move when the picker stick has said movement, a rockable lever, means to rock said lever when the strap is moved by said picker stick, a picker stick checking arm, and a yielding connection between said lever and the arm, rocking of the lever causing the arm to move toward picker stick checking position by a force derived from the lever and transmitted through the yielding means.

9. In a picker stick check for a loom having a

lay and a shuttle box thereon to receive a shuttle and having a picker stick to be given a movement toward the end of the lay by the shuttle as the latter approaches the end of its travel in the shuttle box, a flexible strap to be engaged by the picker stick when the latter has said movement and the picker stick thereby causing movement of one end of the strap, a rockable lever, means to connect the lever operatively to the strap to cause rocking of the lever when said strap is moved by the picker stick, a shuttle checking arm, a bolt connecting the lever and the arm, a compression spring surrounding the bolt and tending normally to move the arm in a direction from the lever to the stick, and stop means to limit motion of the arm with respect to the lever, rocking of the lever by said strap and means moving the arm to picker stick checking position and the arm being movable relatively to the lever when in picker stick checking position by reason of compression of the spring.

10. In a picker stick check for a loom having a lay and a shuttle box thereon to receive a shuttle and having a picker stick to be given a movement toward the adjacent end of the lay by the shuttle as the latter approaches the end of its travel into the shuttle box, two means each capable of resisting movement of the picker stick, one of said means being flexible and having engagement with the outer edge and a side of the picker stick to be moved by the picker stick when the latter has said movement, and the other means being moved by the first means against said first means to force the latter against said side of the picker stick to assist in resisting movement of the picker stick toward the adjacent end of the lay when said first means is moved by the picker stick.

HARRY A. DAVIS.
